(57) **CLAIM**

The ornamental design for a controller for broadcast lenses, as shown and described.

DESCRIPTION

FIG. 1 is a front view of a controller for broadcast lenses in a first configuration of use;

FIG. 2 is a back view thereof;

FIG. 3 is a top view thereof;

FIG. 4 is a bottom view thereof;

FIG. 5 is a left side view thereof;

FIG. 6 is a right side view thereof; and

FIG. 7 is a perspective view thereof.

FIG. 8 is a front view of a controller for broadcast lenses in a second configuration of use;

FIG. 9 is a back view thereof;

FIG. 10 is a top view thereof;

FIG. 11 is a bottom view thereof;

FIG. 12 is a left side view thereof;

FIG. 13 is a right side view thereof; and,

FIG. 14 is a perspective view thereof.

The broken lines show portions of the controller for broadcast lenses that form no part of the claimed design.

1 Claim, 14 Drawing Sheets
